UNITED STATES PATENT OFFICE.

HOWARD HARPER FLICK, OF LEHIGHTON, PENNSYLVANIA.

HAIR-CLIPPER.

1,246,734.

Specification of Letters Patent. Patented Nov. 13, 1917.

Application filed April 25, 1916. Serial No. 93,502.

To all whom it may concern:

Be it known that I, HOWARD H. FLICK, a citizen of the United States, residing at Lehighton, in the county of Carbon and 5 State of Pennsylvania, have invented new and useful Improvements in Hair-Clippers, of which the following is a specification.

This invention relates to a hair clipper and more particularly to that type of clipper 10 used by barbers in trimming the hair at the back and sides of a person's head.

The primary object of the invention is to provide a hair clipper of the class described having connected therewith a movable comb 15 connected with mechanism arranged between the handles of the clipper and operated thereby to swing the comb toward and away from the clipper and to enable an inexperienced person when cutting hair with 20 the clipper to obtain the desired taper to the hair at the back and sides of the person's head.

Another object of the invention is to provide mechanism for imparting swinging 25 movement to the comb connected with the clipper, which may be arranged between the handles of the clipper in such a manner that all parts of said mechanism will be exposed to enable the same to be easily sterilized 30 after the clipper has been used.

With these and other objects in view, the invention resides in the novel combination and arrangement of parts which will be hereinafter described and particularly pointed 35 out in the claim.

The preferred embodiment of the invention has been illustrated in the accompanying drawing, although no restriction is necessarily made to the precise details of construction therein shown, as changes, alterations, and modifications within the scope of 40 the claim may be resorted to when desired.

Like characters of reference denote corresponding parts throughout the several 45 views in the drawing, in which:

Figure 1 is a top plan view of a hair clipper constructed in accordance with the invention.

Fig. 2 is a side elevation of Fig. 1 showing 50 the comb in active position.

Fig. 3 is a bottom plan view of the hair clipper showing the comb in contact with the body of the clipper.

Referring now to the drawing in detail, 55 the numeral 1 designates a hair clipper of the type now in common use having a guard

2 upon which is mounted to slide a cutting bar 3 operatively connected with a movable handle 4 disposed beneath a head 5 provided with a fixed handle 6. 60

Trunnions 7 extend laterally from opposite sides of the guard 2 adjacent the rear end thereof and have mounted thereon ears 8 arranged upon opposite sides of a head 9 of a comb 10 disposed beneath the guard 2 65 and of substantially the same shape as said guard. The teeth 11 on the comb 10 extend the entire length of the guard 2 and when said comb is in inactive position are adapted to lie against the underface of the guard. 70

The head 9 has formed integral therewith between its ends an arm 12 which extends laterally from said head and is offset, as at 13, so that the arm 12 for a portion of its length extends between the handles 4 and 6 75 of the hair clipper in the rear of the head 5. A coiled expansion spring 14 is arranged above the offset 13 in the arm 12 and interposed between said arm and the rear end of the head 5, said spring normally exerting an influence on the arm 12 to hold the teeth on the head of the comb in contact with the underface of the guard 2. 80

A bracket 15 is fixed to the fixed arm 6 of the hair clipper and extends laterally 85 therefrom in the rear of the arm 12 and is provided with a bearing stud 16 upon which is mounted to turn a cam wheel 17.

The cam wheel 17 is provided with a curved edge 18 adapted to contact with the 90 arm 12 above the offset therein, so that when said wheel is turned about the bearing stud 16 the comb will be turned about its pivotal connection with the guard 2 against the influence of the spring 14. 95

The cam wheel 17 has formed therein a recess 19 adapted to have positioned therein at intervals during the turning movement of the cam wheel, the portion of the arm 12 above the offset 13 therein, to enable the 100 spring 14 to restore the comb 10 to its normal position beneath the guard 2 of the hair clipper.

A yoke 20 is secured to the handle 6 of the hair clipper in the rear of the bracket 15 and is provided with spaced arms 21, a similar yoke 22 is rigidly connected with the removable handle 4 and has spaced arms 23 corresponding to the arms 21 on the yoke 20. 105

A lever 24 having angularly extending arms 24' and 24'' is fulcrumed at the junction of the arms 21 of the 110

yoke 22, the arm 24' which is of greater length than the arm 24'' is pivotally connected at its free end with a link 25, said link also having pivotal connection with the 5 arms 28 on the yoke 22, so that when the movable handle 4 is moved toward the fixed handle 6, the lever 24 will be rocked.

A ratchet wheel 27 is secured to one face of the cam wheel 17 and a rod 28 extends 10 inwardly from the inner face of the handle 6 between the yoke 20 and bracket 15, said rod having a looped end 29 in which is mounted to slide a bar 30 one end of which is pivotally connected with an end on the 15 arm 24'' on the lever 24, said bar being provided with teeth 31, said teeth being caused to engage with the teeth on the ratchet wheel 27 as the lever 24 is rocked by movement of the movable handle 4 by the loop on the rod 20 28 which serves as a combined support and guide for the bar.

Through the above described arrangement of the cam wheel 17, lever 24, and bar 30, it will be seen that the mechanism for imparting turning movement to the cam wheel is so arranged that the various parts thereof will at all times come in contact with the sterilizing medium when the hair clipper is placed 25 therein and that the parts of said mechanism are so arranged that they may be easily 30 cleaned without disconnecting the same.

When it is desired to trim the hair at the back and sides of a person's head, the handle 4 is operated until the upper end of the arm 35 12 is positioned in the recess 19 in the cam wheel which allows the upper face of the teeth 11 on the comb to be brought into contact with the underface of the guard 2 through the action of the spring 14.

40 The comb may now be placed against the neck of the person whose hair is to be trimmed and as the handle 4 is operated to impart sliding movement to the cutting bar as the clipper is moved upwardly, the lever

24 will be rocked and the bar 30 drawn backwardly and forwardly across the ratchet wheel 27, such movement turning the cam wheel 17 and gradually moving the comb teeth away from the guard 2, so that the hair is cut with the desired taper. 45 50

When the cam wheel 17 has been turned until the recess 19 therein registers with the upper end of the arm 12, the spring 14 will turn the comb head about its pivotal connection with the guard 2 and cause the 55 comb to assume its normal position beneath said guard.

From the foregoing description, taken in connection with the accompanying drawing, it is at once apparent that a hair cutter has 60 been provided which will enable an inexperienced person to cut hair at the back and sides of a person's head with the required taper and that a clipper of the class described has been provided in which mechanism for imparting swinging movement to a comb connected therewith is so arranged in the rear of the comb and between the handles of the clipper as to be easily sterilized and cleaned when the occasion requires. 65 70

Having thus described the invention, what is claimed as new, is:

In a device of the class described, a hair clipper, a comb mounted to swing thereon, yokes on the arms of the clipper, a rod on 75 one of said arms having a loop therein, means for swinging said comb when the arms of the clipper are operated including a toothed bar mounted to slide in said loop, a lever pivotally connected with an end of 80 said bar and fulcrumed upon one of said yokes, and a link pivotally connected with the other yoke and the lever.

In testimony whereof I affix my signature.
HOWARD HARPER FLICK.
